Primary Examiner — Stella Reid*Assistant Examiner* — Janice Lim(74) *Attorney, Agent, or Firm* — Gordon & Jacobson, PC(57) **CLAIM**

The ornamental design for a shoe, as shown and described.

DESCRIPTION

FIG. 1 is a front perspective view of a shoe, showing my new design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The broken line portions of FIGS. 1-7 are included to show unclaimed subject matter only and form no part of the claimed design.
